UNITED STATES PATENT OFFICE.

THOMAS HOLVERSON, OF WASHINGTON, DISTRICT OF COLUMBIA.

PLAYER-PIANO.

1,252,111.

Specification of Letters Patent.

Patented Jan. 1, 1918.

Application filed August 17, 1917. Serial No. 186,770.

To all whom it may concern:

Be it known that I, THOMAS HOLVERSON, a citizen of the United States, and a resident of Washington, in the District of Columbia, 5 have invented new and useful Improvements in Player-Pianos, of which the following is a specification.

My invention is an improvement in player pianos, and has for its object to provide 10 mechanism for connecting the pneumatics with the wind trunk, in such manner that any individual pneumatic may be removed without disturbing the others should such removal be necessary for any reason.

15 In the drawings:

Figure 1 is a perspective view of a portion of the mechanism of a piano player;

Fig. 2 is a central longitudinal section;

20 Fig. 3 is a perspective view of a part of the supporting mechanism for the wind trunk and the pneumatics;

Fig. 4 is a perspective view of one end of the pneumatic.

In the present embodiment of the invention, the frame 1 which carries the two tiers 25 of pneumatics is connected and supported in the usual manner, and the wind trunks which supply the respective tiers are, as usual, substantially right triangular in cross 30 section, having their hypotenuse sides rounded. The pneumatics 3, which are of the usual construction, are detachably connected with the wind trunks and with the channel plates 4 which are supported by the 35 frame at the rear of the respective tiers of pneumatics. These plates are arranged with their channels upward, and the pneumatics with the valves 5 are supported between the channel plates and the wind trunks.

40 The pneumatics are arranged with their upper surfaces in contact with the base of the wind trunk and the valve boxes abut at their forward ends against the rear wall of the wind trunk. Each valve box has an up- 45 standing pin 6 at its forward end, and a curved clamping plate 7 engages the rounded side of the wind trunk and has depending lugs 8 at its forward end which are secured to the front end of the pneumatic, as indicated at 9, and the plate has a slot 10 at its upper end for receiving the pin 6. It will be noticed that the pin 6 and the pins 9 which engage the slot 10 and the lugs 8, respectively, are beveled in such manner that

50 55 when the slot 10 is engaged with the lug 6

the openings of the lugs 8 may be slipped over the pins 9.

The channel plates are notched at each pneumatic in their forward sides, as indicated at 10°, the notches extending through 60 the front side wall and into the bottom, and the notch in the front wall is for permitting the passage of the rearwardly extending plate 11 which is secured to the fixed member of the pneumatic at the rear end thereof. 65 The regulating pin 12 of the movable member of the pneumatic extends through the notch in the bottom of the plate and through the plate 11, as shown in Fig. 2, and the stop 12a on the pin has a cushion 13 of felt or the 70 like for engaging the plate 4.

To remove the pneumatic it is only necessary to spring the lugs 8 outwardly to detach them from the pins 9, after which the plate 7 may be easily detached from the lug 6. By 75 moving the front end of the pneumatic downward it may be disengaged from the wind trunk, the regulating pin 12 slipping out through the notch in the channel plate. A reversal of this motion will connect the 80 pneumatic to the wind trunk and the plate 4. It will be noticed that each of the plates 7 has an opening 13 at its front, and a portion of the material of the plate at the rear of the opening is turned up as indicated at 14 to 85 form a finger piece for assisting in holding the plate in place during the placing of the plate.

In placing the plate, the slot 10 is first engaged with the lug 6. The pneumatic then 90 is held up by the fingers, while the plate is held down by the thumb engaging the up-turned portion of the finger piece 14, and the parts are so held until the pins are engaged with the openings. It will be noticed that 95 at each of the openings 13 the wind trunk 2 has an opening which is normally closed by a rubber plug or button 15. The valve box or casing may be cleaned, without removing it from its place, from obstructions near the 100 wind trunk by simply removing the plug 15, and it is not necessary to remove the pneumatic for this purpose.

The valve casing 5 is of metal, and each of the said casings consists of a body, as 105 shown, of substantially rectangular outline, the inner edges of the side and end walls of the body being rabbeted, as shown at 16, and a cover 17 is fitted into the rabbet. The covers are of such size that they may be 110

snapped into the rabbet and will be held in such position by friction, the friction being assisted by the rearward projection of the plate 7.

5 It will be understood that instead of metal the valve casing may be of fiber, composition or the like. The mounting of the player action is small and compact, permitting the removal of the keys without interfering with 10 the player action.

A stop 12^a is adjustably connected with the regulating pin, being threaded thereon as shown, and a washer 13, of felt or the like, is arranged at the top of the stop for engaging 15 a channel plate 4.

The channel plates 4 are connected to the cross bars 1^a of the frame 1, by any suitable means, to support the said plates in the proper position.

20 I claim:

1. In a player piano, the combination with the pneumatics, the wind trunks, and the supporting frame for the trunks, the frame having channel plates for engagement by 25 the rear ends of the pneumatics, each chan-

nel plate having a notch in the side wall and bottom at each pneumatic and the pneumatic having an extension extending into the notch above the bottom of the channel plate, and a clasp plate passing over the wind 30 trunk at the front end of the pneumatic and having a detachable connection at each end with the pneumatic, said connection comprising pins on the pneumatic and openings in the clasp plate for engagement by the 35 pins.

2. In a player piano, the combination with the pneumatics, the wind trunks, and the supporting frame for the trunks, the frame having channel plates for engagement by the 40 rear ends of the pneumatics, each channel plate having a notch in the side wall and bottom at each pneumatic and the pneumatic having an extension extending into the notch above the bottom of the channel plate, and a clasp plate passing over the wind 45 trunk at the front end of the pneumatic and having a detachable connection at each end of the pneumatic.

THOMAS HOLVERSON.
